[57] CLAIM

The ornamental design for a decorator wall panel, as shown and described.

DESCRIPTION

FIG. 1 is a perspective view of an array of decorator wall panels, showing our new design, with the room shown in broken lines for illustrative purposes only and forming no part of the claimed design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a side elevational view thereof, the opposite side elevational view being identical thereto.
